(57) **ABSTRACT**

A new and distinct cultivar of *Calibrachoa* plant named 'Suncal 1941', characterized by its semi-upright and mounding plant habit; vigorous growth habit; freely branching habit; freely flowering habit; long flowering period; large purple violet-colored flowers with yellow-colored centers; and good garden performance.

1 Drawing Sheet

1

Botanical designation: *Calibrachoa* sp.

Cultivar denomination: 'SUNCAL 1941'.

BACKGROUND OF THE INVENTION

The present invention relates to a new and distinct cultivar of *Calibrachoa* plant, botanically known as *Calibrachoa* sp. and hereinafter referred to by the name 'Suncal 1941'.

The new *Calibrachoa* plant is a product of a planned breeding program conducted by the Inventor in Higashiomii, Shiga, Japan. The objective of the breeding program is to develop new vigorous, semi-upright, mounding and freely branching *Calibrachoa* plants with numerous large and attractive flowers with unique coloration.

The new *Calibrachoa* plant originated from a cross-pollination conducted by the Inventor in Higashiomii, Shiga, Japan in September, 2012 of a proprietary selection of *Calibrachoa* sp. identified as code number C24-269-2, not patented, as the female, or seed, parent with a proprietary selection of *Calibrachoa* sp. identified as code number C24-162-1, not patented, as the male, or pollen, parent. The new *Calibrachoa* plant was discovered and selected by the Inventor as a single flowering plant from within the progeny of the stated cross-pollination in a controlled greenhouse environment in Higashiomii, Shiga, Japan in October, 2013.

Asexual reproduction of the new *Calibrachoa* plant by terminal vegetative cuttings in a controlled greenhouse environment in Higashiomii, Shiga, Japan since November, 2013 has shown that the unique features of this new *Calibrachoa* plant are stable and reproduced true to type in successive generations.

SUMMARY OF THE INVENTION

Plants of the new *Calibrachoa* have not been observed under all possible combinations of environmental conditions and cultural practices. The phenotype may vary somewhat

2

with variations in environmental conditions such as temperature and light intensity without, however, any variance in genotype.

The following traits have been repeatedly observed and are determined to be the unique characteristics of 'Suncal 1941'. These characteristics in combination distinguish 'Suncal 1941' as a new and distinct *Calibrachoa* plant:

1. Semi-upright and mounding plant habit.
2. Vigorous growth habit.
3. Freely branching habit.
4. Freely flowering habit.
5. Long flowering period.
6. Large purple violet-colored flowers with yellow-colored centers.
7. Good garden performance.

Plants of the new *Calibrachoa* can be compared to plants of the female parent selection. Plants of the new *Calibrachoa* differ primarily from plants of the female parent selection in flower size as plants of the new *Calibrachoa* have larger flowers than plants of the female parent selection.

Plants of the new *Calibrachoa* can be compared to plants of the male parent selection. Plants of the new *Calibrachoa* differ primarily from plants of the male parent selection in flower color as plants of the new *Calibrachoa* have purple violet-colored flowers whereas plants of the male parent selection have pink-colored flowers with a yellow-colored star-shaped pattern.

Plants of the new *Calibrachoa* can also be compared to plants of *Calibrachoa* sp. 'Sunbelao', disclosed in U.S. Plant Pat. No. 22,391. In side-by-side comparisons, plants of the new *Calibrachoa* and 'Sunbelao' differ primarily in the following characteristics:

1. Plants of the new *Calibrachoa* are semi-upright whereas plants of 'Sunbelao' are upright.
2. Plants of the new *Calibrachoa* have shorter leaves than plants of 'Sunbelao'.

3. Plants of the new *Calibrachoa* are more freely flowering than plants of 'Sunbelao'.
 4. Plants of the new *Calibrachoa* have larger flowers than plants of 'Sunbelao'.
 5. Flower petals of plants of the new *Calibrachoa* have emarginate apices whereas flower petals of plants of 'Sunbelao' have apices that are blunt to slightly cordate.

BRIEF DESCRIPTION OF THE PHOTOGRAPHS

10

The accompanying colored photographs illustrate the overall appearance of the new *Calibrachoa* plant showing the colors as true as it is reasonably possible to obtain in colored reproductions of this type. Colors in the photographs may differ slightly from the color values cited in the detailed botanical description which accurately describe the colors of the new *Calibrachoa* plant.

The photograph at the top of the sheet comprises a side perspective view of a typical flowering plant of 'Suncal 1941' grown in a container.

The photograph at the bottom of the sheet is a close-up view of a typical flowering plant of 'Suncal 1941'.

DETAILED BOTANICAL DESCRIPTION

25

The aforementioned photographs and following observations, measurements and values describe plants grown during the summer in 24-cm containers in an outdoor nursery in Higashiomii, Shiga, Japan and under cultural practices typical of commercial *Calibrachoa* production. During the production of the plants, day temperatures averaged 23° C. and night temperatures averaged 13° C. Plants were four months old when the photographs and the description were taken. In the following description, color references are made to The Royal Horticultural Society Colour Chart, 2007 Edition, except where general terms of ordinary dictionary significance are used.

Botanical classification: *Calibrachoa* sp. 'Suncal 1941'.

Parentage:

Female, or seed, parent.—Proprietary selection of *Calibrachoa* sp. identified as code number C24-269-2, not patented.

Male, or pollen, parent.—Proprietary selection of *Calibrachoa* sp. identified as code number C24-162-1, not patented.

Propagation:

Type.—By vegetative terminal cuttings.

Time to initiate roots, summer and winter.—About one week at temperatures about 15° C. to 20° C.

50

Time to produce a rooted young plant, summer and winter.—About three weeks at temperatures about 15° C. to 20° C.

Root description.—Fibrous; white in color.

Rooting habit.—Freely branching.

55

Plant description:

Plant and growth habit.—Semi-upright and mounding plant habit; freely branching habit with numerous lateral branches developing per plant; pinching enhances lateral branch development; vigorous growth habit.

60

Plant height.—About 23 cm.

Plant diameter.—About 73 cm.

Lateral branch description:

Length.—About 30 cm.

65

Diameter.—About 1.8 mm.

Internode length.—About 1.8 cm.

Strength.—Strong.

Aspect.—Upright to outwardly.

Texture.—Densely pubescent; rough.

Color.—Close to 144B.

Leaf description:

Arrangement.—Alternate, simple.

Length.—About 3.7 cm.

Width.—About 2 cm.

Shape.—Elliptic.

Apex.—Obtuse.

Base.—Attenuate.

Margin.—Entire.

Texture, upper and lower surfaces.—Sparsely pubescent; rough.

Venation pattern.—Pinnate; reticulate.

Color.—Developing leaves, upper surface: Close to 138A. Developing leaves, lower surface: Close to 138B. Fully expanded leaves, upper surface: Close to 137C; venation, close to 144B. Developing and fully expanded leaves, lower surface: Close to 138B; venation, close to 145B.

Petioles.—Length: About 6.3 mm. Diameter: About 2.4 mm. Texture, upper and lower surfaces: Pubescent. Color, upper and lower surfaces: Close to 144B.

Flower description:

Flower arrangement and habit.—Single salverform flowers arising from upper leaf axils; freely flowering habit with usually about 300 flowers developing per plant; flowers face upright to outwardly.

Fragrance.—None detected.

Natural flowering season.—Early flowering habit, plants of the new *Calibrachoa* initiate and develop flowers about three to four weeks after planting; long flowering period, flowering naturally commences during the spring and plants flower continuously throughout the summer until late autumn in Japan.

Flower longevity.—Individual flowers last about seven to ten days on the plant; flowers not persistent.

Flower diameter.—About 4 cm.

Flower length (depth).—About 9.2 mm.

Throat diameter.—About 9.3 mm.

Tube length.—About 1.8 cm.

Tube diameter, base.—About 2.9 mm.

Flower buds.—Length: About 2.2 cm. Diameter: About 9.4 mm. Shape: Cylindrical. Color: Close to 83C.

Corolla.—Arrangement: Five petals fused at the base and opening into a flared trumpet. Petal length from throat: About 1.6 cm. Petal width: About 1.9 cm. Petal shape: Roughly spatulate. Petal apex: Emarginate. Petal margin: Entire; slightly undulate. Petal texture, upper and lower surfaces: Smooth, glabrous. Throat texture: Smooth, glabrous. Tube texture: Smooth, glabrous. Color: Petal, when opening, upper surface: Close to N81A. Petal, when opening, lower surface: Close to N82B. Petal, fully opened, upper surface: Close to N82A; towards the throat, close to 83B and 85A; venation, faint, close to 83B; color becoming closer to N82B with development. Petal, fully opened, lower surface: Close to 85A; venation, close to 83B; color does not change with development. Throat: Close to 3B; venation, faint, close to 144C. Tube: Close to 2C; venation, close to 144C.

Calyx.—Arrangement: Star-shaped tubular calyx tube with five sepals in a single whorl and fused at the

base. Sepal length: About 9.3 mm. Sepal width: About 2.9 mm. Sepal shape: Lanceolate. Sepal apex: Acute. Sepal margin: Entire. Sepal texture, upper and lower surfaces: Pubescent. Sepal color: Immature and mature, upper surface: Close to 144A. 5 Immature and mature, lower surface: Close to 144A.

Peduncles.—Length: About 1.5 cm. Diameter: About 0.8 mm. Angle: Upright to outwardly. Strength: Strong. Texture: Pubescent. Color: Close to 144A.

Reproductive organs.—Stamens: Quantity: Five per flower. Filament length: About 9 mm. Filament color: Close to 145C. Anther shape: Ellipsoidal. Anther size: About 1.5 mm by 1.2 mm. Anther color: Close to 3C. Pollen amount: Moderate. Pollen color: Close to 4C. Pistils: Quantity: One per flower. Pistil length: About 1 cm. Style color: Close to 145C. 10

Stigma shape: Transversely ellipsoidal. Stigma color: Close to 145B. Ovary color: Close to 145A.

Seeds and fruits.—To date seed and fruit development have not been observed on plants of the new *Calibrachoa*.

Garden performance: Plants of the new *Calibrachoa* have been observed to have good garden performance and to tolerate wind, rain and temperatures ranging from about 5° C. to about 35° C.

10 Pathogen & pest resistance: To date, plants of the new *Calibrachoa* have not been observed to be resistant to pests and pathogens common to *Calibrachoa* plants.

It is claimed:

1. A new and distinct *Calibrachoa* plant named 'Suncal 15 1941' as illustrated and described.
